(57) **CLAIM**

We claim the ornamental design for a grille for a speaker housing, as shown and described.

DESCRIPTION

FIG. 1 is a front perspective view of one embodiment of a grille for a speaker housing showing our new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a front perspective view thereof showing an environment in which the grille for a speaker housing is used;

FIG. 10 is a front view thereof showing an environment in which the grille for a speaker housing is used;

FIG. 11 is a front perspective view of another embodiment of a grille for a speaker housing showing our new design and showing an environment in which the grille for a speaker housing is used; and,

FIG. 12 is a left side perspective view thereof showing an environment in which the grille for a speaker housing is used. The broken line elements in the drawings are shown solely to illustrate environments in which our new design is used, and form no part of the claimed design.
